DESIGN FOR A PAPERBOARD

Irving Blechman, Bronx, N. Y.

Application December 12, 1939, Serial No. 88,847

Term of patent 14 years

To all whom it may concern:

Be it known that I, Irving Blechman, a citizen of the United States and resident of the Bronx, in the county of Bronx and State of New York, have invented a new, original, and ornamental Design for a Paperboard, of which the following is a specification, reference being had to the accompanying drawing, forming part thereof.

The figure is a face view of a swatch of paperboard showing my new design.

I claim:

The ornamental design for a paperboard, substantially as shown.

IRVING BLECHMAN.
